(57) **CLAIM**

The ornamental design for an orthosis, as shown and described.

DESCRIPTION

FIG. 1 is a front elevation view of an orthosis;

FIG. 2 is a left side elevation view of the orthosis;

FIG. 3 is a rear elevation view of the orthosis;

FIG. 4 is a right side elevation view of the orthosis;

FIG. 5 is a top side view of the orthosis;

FIG. 6 is an isometrical view of the orthosis; and,

FIG. 7 is an isometrical view of a second embodiment of the orthosis of FIGS. 1-6, it being understood that all surfaces are the same as those of the first embodiment, the only difference being that the disclaimed wedge portion.

The broken lines in FIG. 7 showing a wedge portion illustrate environmental structure and form no part of the claimed design.
